UNITED STATES PATENT OFFICE.

JAMES WRIGHT AND HEBDEN WRIGHT, OF INGROW, NEAR KEIGHLEY,
ENGLAND.

SPINNING-MACHINE SPINDLE AND ITS APPURTENANCES.

No. 846,375.

Specification of Letters Patent.

Patented March 5, 1907.

Application filed September 14, 1905. Serial No. 278,359.

To all whom it may concern:

Be it known that we, JAMES WRIGHT and HEBDEN WRIGHT, subjects of the King of Great Britain, and residents of The Whins, Ingrow, near Keighley, in the county of York, England, have invented certain new and useful Improvements in Spinning-Machine Spindles and Their Appurtenances, of which the following description, together with the accompanying sheets of drawings, is a specification.

The class of machinery to which our invention relates is that styled "flier" spinning, doubling, twisting, and like machines or frames, and especially to such machines of this class wherein fliers are used and rotated independently of their spindles, their said spindles being stationary while the fliers are formed to be supported by them at their upper as well as at their lower extremities. As is well known, these fliers are produced of this formation or construction to enable them to be rotated at comparatively high rates of speed without engendering excessive vibratory movements, and while we have found this to be possible we have also found that although the encircling of the thread around one or other of the legs of the flier gives fairly good results as to the smoothening of the yarn or straightening of the fibers, yet certain of such fibers are by the rotary motions transmitted to them caused to radiate or extend from the yarn.

To construct a flier that shall be enabled to mitigate if not entirely obviate the production of yarns with stray fibers extending from them is the object of our present invention. To attain this object, we construct the flier and arrange means whereby its use may be as freely enjoyed as is that of the common or ordinary flier, such improved flier and means being illustrated by the accompanying sheets of drawings, wherein—

Figure 1 is an elevation showing our improved flier mounted upon its spindle and other parts arranged in connection therewith. Fig. 2 is a sectional elevation of certain of the parts shown by Fig. 1. Fig. 3 is an elevation of our improved flier as detached or removed from the spindle, and other parts. Fig. 4 is a sectional plan on line A B of Fig. 1. Fig. 5 is front elevation of a sufficient portion of a spinning or like machine to illustrate the application of our

invention, and the spindles illustrated are shown in their operating positions. Fig. 6 is a sectional end elevation of the parts shown by Fig. 5 and as seen in the direction indicated by the arrow C. Figs. 7 and 8 are similar views to Figs. 5 and 6, respectively, but illustrate the fliers as being raised into position to allow the process of "dofling."

Similar letters and figures of reference indicate similar parts throughout the several views.

D indicates the fixed framework of the machine.

In carrying our invention into effect we make use of a flier having its legs *a* formed to be supported vertically at its upper end and laterally at its lower end by its stationary spindle *b*, by which support or bearings it is held so that its driving-tape on passing around its pulley *c* may transmit rotary motion to it at a comparatively high rate of speed without undesirable vibratory motions being set up thereby.

The bobbin *d* is mounted to be placed over the spindle *b* and rest upon the disk *e*, carried by the tube or sleeve *f*, fixed to the rail *g*, known as the "lifter-rail," which has rising-and-falling motion transmitted to it in the well-known manner for moving the bobbins *d* vertically for the well-known purposes.

To enable the "wiring" or encircling of the thread or yarn being treated around the leg of the flier (as in the oldest style of flier) as said thread is being conducted to the bobbin *d*, upon which it is to be wound, we make use of additional legs, hereinafter referred to as "arms" *h h*, which have their lower ends free, so that the usual form of curved or curled parts *k k* may be formed on them to act in the well-known manner as thread-guide eyes.

The parts formed and constructed as above described are similar to what is shown in Letters Patent No. 712,886, granted to us November 4, 1902, and are already well known and in use, and to these parts we add our improvements as follows: Between the legs *a a* of the flier we mount an annular piece *m*, which is so situated relatively with eyes *k k* of the arms *h h* that the thread after passing around one or the other of the arms *h h*, as in said patent, and through the openings in one or other of the said eyes, is made to pass over and in contact with the upper edge of the annular part *m* before such thread is

wound upon its bobbin *d*, by which means the otherwise stray or unwound-in fibers are brought into line with the others, forming the yarn or thread, which is thus made 5 smooth, as desired. The annular piece *m* is preferably fixed to the legs *a a* of the flier by lateral indents being made in said legs for the reception of the annular piece *m*, so that while the said legs *a a* are as close to the 10 outer surface of the full bobbin *d* as circumstances will permit this annular piece *m* will not be so near to said bobbin *d* as to be detrimental to or so as to interfere with its operations.

15 To make possible the use of fliers having annular pieces *m* and otherwise constructed as above described without increasing the care, labor, and attention of the operative when doffing or carrying out other parts of 20 the process of yarn or thread production, we arrange a plate or rail *p* to be supported by vertical racks *g*, (one at each end of the series of spindles, but only one being shown,) which are operated by the toothed wheels *r*, mounted 25 on the shaft *s*, to which is secured the handle-lever *t*, so that during the ordinary operations of the fliers the plate or rail *p* remains in its inoperative position shown by Figs. 5 and 6, while when the process of doffing 30 has to commence the ordinary lifter-rail *g* is raised to its highest position to take the bobbins *d* as near to the tops of the spindles *b* as possible, on which the handle *t* is turned over into the position shown by Fig. 8, (where 35 it is held by the holding-piece *v*, pivoted to the frame,) by which movement the racks *g* will be raised to cause the rail *p* to lift the fliers *a* into the positions shown by Figs. 7 and 8, from which positions they may be 40 easily removed and replaced by others, as will be understood. At the time the plate *p* is being raised the board or thread-guide *w* is also raised by being coupled thereto by a slotted rod, as shown in broken lines, Figs. 6 45 and 8, or this board *w* may be raised by the handle *x* and held in its raised position by this latter resting upon the stop-piece *y* should this be thought to be more desirable.

Such being the nature and object of our 50 invention, what we claim is—

1. In spinning machinery of the class described, a flier constructed to be supported at its upper and lower extremities, and hav-

ing one or more side arms with free ends to enable the yarn or thread to pass around the same, said flier also having an annular piece mounted in position to guide said thread after it leaves the flier-arm and before it is wound on the bobbin, a spindle for supporting said flier, and means for transmitting motion thereto, substantially as herein specified. 55

2. In spinning machinery of the class described, a flier having legs supported at both ends and having arms the ends of which are 60 free and formed to guide the yarn or thread being produced, a supplementary guiding part fixed on said flier for guiding the thread after it leaves the arms of said flier, a spindle for supporting said flier, a tube or sleeve on 65 said spindle to support a bobbin thereon, and means for transmitting vertical motion to said sleeve and said flier, substantially as herein specified. 70

3. In spinning machinery of the class described, a flier having legs supported at both ends and having arms with free ends and having an annular piece mounted in position to guide the thread after it leaves the flier-arms and before it is wound on the bobbin, a 75 spindle for supporting said flier, a tube or sleeve taking over said spindle to support the bobbin and said flier, and means for raising said flier to facilitate the process of doffing, substantially as herein specified. 80

4. In spinning machinery of the class described, a flier having legs supported at both ends and having arms with free ends and having an annular piece mounted in position to guide the thread after it leaves the flier-arms and before it is wound on the bobbin, a 85 spindle for supporting said flier, a tube or sleeve on said spindle to support the bobbin thereon, means for transmitting motion to said sleeve and said flier, means for raising 90 said flier, and means for raising the guide-board to facilitate the process of doffing, substantially as herein specified. 95

In testimony whereof we have affixed our signatures in the presence of two witnesses. 100
